ROLLABLE WINDOW SCREEN

Harry W. Thomas, Miami Beach, Fla., assignor to
Irving Rossi, New York, N. Y., as trustee

Original application March 16, 1940, Serial No.
324,395. Divided and this application April 4,
1944, Serial No. 529,432

3 Claims. (Cl. 160—133)

1

This invention is a division of my application Serial No. 324,395 filed March 16, 1940, which has eventuated into Patent 2,349,225 of May 16, 1944, and relates to a rollable sheet for covering window openings.

Specifically my invention contemplates a rollable sheet made of a series of slats of synthetic thermally workable material, the slats being laminated together, the joints between the slats in different laminations being staggered with respect to each other. Preferably, but not necessarily, the slats should be transparent or translucent. A preferred material for my invention is Nylon although many other materials such as Vynylon, vinyl resins, aldehyde condensation products, cellulose derivatives, Alsifilm and other thermoplastic or thermo-setting synthetic materials may be used.

A rollable window screen of the type of my present invention may be used in connection with either opaque or transparent rollable solid material, such as an opaque or transparent sheet of Nylon, or an opaque or transparent sheet of relatively inflexible material laminated or laid together in such a manner as to render it flexible.

The screen and the opaque or transparent sheet may be so interconnected that the raising or lowering of one will complementarily lower or raise the other; and the opaque or transparent sheet may, if desired, be used without a screen.

A rollable window screen of the type of my invention may also be utilized in connection with a sliding window sash and may be attached thereto in any suitable manner.

Many other objects and uses of this invention will in part be apparent and in part pointed out in the following description and drawing in which

Figure 1 is a fragmentary perspective showing one form of edge binding of the rollable window screen;

Figure 2 is a fragmentary perspective showing the use of the rollable window screen of my invention in connection with a sliding window sash;

Figure 3 is a fragmentary perspective showing the utilization of the rollable window screen of my invention in connection with a rollable sheet; and

Figure 4 is a fragmentary view of a portion of the rollable sheet of Figure 3.

Referring to Figure 1, I have shown a portion of a rollable window screen comprising the screening material 20 which in normal operation in the window frame may be subjected to lateral

2

tension in the direction shown by the arrows 83. This rollable window screen has a binding 80 secured thereto in the manner described in my patent for Screen frames, Patent No. 2,297,729, issued October 6, 1942.

This binding 80 may have openings 82 therein in which grommets of the type 66 may be inserted in order to aid in securing or which may be used for securing purposes in the condition in which they appear in Figure 1.

These openings 82, when the screen 20 is subjected to the lateral tension indicated by the arrows 83, are subjected to a tension at their edges in a direction indicated by the arrows 84 and accordingly the binding means 80 should be of sufficient strength to resist this tension.

However, the space between the arrows 84 is not necessarily subjected to counterbalancing tension and hence since the material 80 is preferably elastic and flexible, this material may yield to the tension indicated by the arrows 83 and may thus be pulled out of the guides or, at the very least, unsightly gaps may occur.

In order to provide lateral stability which will prevent this result while at the same time retaining the flexibility of the binding of the screen, I have provided for the insertion within the binding 80 at the edge thereof of a flexible metal strip 81 which may be placed in the rolling position

but which will be rigid with respect to transverse forces and thus will serve to maintain the lateral stability of the binding without interfering with the rollability of the screen. Since the metal strip 81 by reason of its cross-section will not yield when tensioning forces are produced thereon in the direction indicated by the arrows 83, unsightly gaps or the possibility of escape of the screen from its guides are obviated.

In Figure 3 I have shown the application of my rollable window screen 20 to a window which is also to have a rollable transparent or opaque sheet material which will come into the opening as the screen is withdrawn therefrom or which will be withdrawn from the window opening as the screen is drawn thereinto.

The rollable window screen is at 100 mounted in the top 101 of the window and the edge 106 thereof is supported in suitable guides in the manner hereinbefore described. The rollable transparent or opaque sheet 102 having an edge 107 adapted to cooperate with window guides is also mounted on preferably a spring roller 103 which in turn is rotatably mounted within the roller box 104 preferably located just beneath the window sill.

The screen 20 and the rollable sheet 102 are interconnected at 105 in the manner shown; that is, the bar at the bottom of the screen may be interconnected with a similar bar at the top of the rollable sheet 102.

Either the screen 20 or the rollable sheet 102 may be operated individually and for this purpose it is desirable that the interconnection therebetween at 105 should be a releasable one and hence should be effected by releasable fastening devices such as clips, toggles, hooks, spring clips, snap fasteners, releasable locks, turn studs or any other suitable but releasable fastening means.

When the screen 20 and the rollable sheet 102 are thus disconnected, then either or both members may be permitted to be rewound on their respective rollers. In such case also, either or both members may be unwound from their respective rollers and left in any suitable position by being secured to their window guides in the manner previously pointed out or any other suitable manner.

The thin transparent or translucent or opaque flexible material forming rollable sheet 102 may be made of any suitable material which itself is inherently flexible or rollable or may be made of any material which may be formed in such a manner as to be flexible or rollable. The material of which the rollable sheet may be made thus includes all of the materials heretofore mentioned including Nylon or any other inorganic or organic material, as well as cellulose derivatives of various kinds and acetate materials.

Where the material itself in sheet form is not inherently sufficiently flexible for the purpose, then it may be laminated in any suitable manner or hinged in any suitable manner to obtain the desired flexibility.

Thus as seen in Figure 4, the sheet 102 may consist of strips of nylon 110 and 111 laminated together with staggered joints 112. The joints 112 by reason of the fact that they are staggered in the manner shown in Figure 4 permit even a slight amount of flexibility in each of the slats 111 and 112 to have a cumulative effect which permits the sheet to be rollable.

The sheet 102 where it is not desired to form it in the manner shown in Figure 4 or where it itself is not necessarily inherently flexible may be formed around an open wire netting or such wire netting or reinforcing may be an interlayer between two sheets of the transparent, translucent or opaque flexible material which are cemented together or joined in an autoclave or in any other suitable apparatus.

The flexible sheet 102 need not necessarily be mounted at the bottom of the window as seen in Figure 3 but may be mounted at the top or at the side in any suitable manner to provide for a semi-permanent or permanent slidable covering for the window or a louvre for the window or may be similarly used in any form of window construction.

Flexible elastic tapes of the type hereinabove described and of the type described in my above-mentioned patent for screen frames may be applied at the longitudinal edges in order to provide

for proper guidance and support of the sheet material.

In Figure 2 I have shown the combination of the rollable window screen 20 of my invention with a window which may, if desired, be a storm window, the window and screen being connected so that the raising or lowering of the window sash will result in the bringing of the screen 20 into or out of the window opening.

Both the screen 20 and the window sash 90 may operate in suitable guides in the jamb 93 of the window frame. The sash 90 and the screen 20 may be interconnected in any suitable manner. Thus, for instance, as seen in Figure 2, the top of the window sash may carry a rigid bar 91 having a channel or suitable groove therein and the bar of the screen 20 may carry a similar bar 92 formed and arranged to interengage with the bar 91. These cooperating bars 91 and 92 may be of metal or plastic material or of any other suitable material.

These bars 91 and 92 may easily be disengaged to permit separate operation of the sash or the screen.

While the manner of engagement between the bars 91 and 92 shown in Figure 2 is preferred, any other suitable readily releasable engagement means may be utilized for this purpose.

I have here described but a few of the uses of my rollable window screen and only the preferred forms of construction in which the same may be embodied. Many other uses of the rollable window screen or of the rollable sheet hereinabove set forth will now be obvious to those skilled in the art.

Many other types of bindings falling within this invention will now be obvious from the foregoing description and many other types of screen materials and the combination therewith of bindings of various types which will not interfere with rollability will also be obvious and many other uses of such rollable screens will also be clear to those skilled in the art. I prefer therefore to be limited not by the specific disclosures hereinabove set forth but only by the appended claims.

I claim:

1. A rollable sheet for window openings, said sheet being made of transparent synthetic thermally workable material and being mounted on a roller, and windable on and off said roller, said sheet comprising a series of slats of said material, laminated together, the joints between the slats in different laminations being staggered with respect to each other.

2. A rollable sheet for window openings, said sheet being made of transparent synthetic thermally workable material and being mounted on a roller, said sheet comprising a series of slats of said material, laminated together.

3. A rollable sheet of synthetic thermoplastic material, said sheet comprising a series of slats of said material laminated together, the joints between the slats in different laminations being staggered with respect to each other.

HARRY W. THOMAS.
